UNITED STATES PATENT OFFICE.

JOHN KAYLOR, OF DECATUR, ILLINOIS.

CHECK-ROW LEVER FOR CORN-PLANTERS.

SPECIFICATION forming part of Letters Patent No. 672,559, dated April 23, 1901.

Application filed March 16, 1901. Serial No. 51,454. (No model.)

To all whom it may concern:

Be it known that I, JOHN KAYLOR, of the city of Decatur, county of Macon, and State of Illinois, have invented certain new and useful Improvements in Check-Row Levers for Corn-Planters, of which the following is a specification.

This invention relates to the forked levers used on check-row corn-planters to impart motion from the knots on the check-row wire to dropping mechanism of the planter, and its utility will hereinafter appear. It is exemplified in the structure hereinafter described, and it is defined in the appended claims.

Check-row levers are made in various forms. Some swing in a horizontal plane and others swing in a vertical plane, and they transmit force to the dropping mechanism in various ways. The forked ends of the levers are, however, substantially the same in all practical planters at present manufactured, and in all cases the levers are thrown in one direction by the resistance of the relatively stationary knots on the check-row wire and are returned by spring-pressure. The bars of which the forks of a lever are composed extend parallel one with the other throughout the impact part of the lever, and they diverge at their ends to form a releasing-space and to insure the proper straddling of the wire by the fork as the lever is returned by the spring. The lever extends across the wire and is either presented forward or held at approximately right angles with the wire while traveling from one knot to another, the normal position of the lever depending on various requirements in different planters, and in every case the lever is swung backward by the resistance of the knots as the planter travels forward until the impact-surface of the fork forms a sliding angle or an incline on which the knots may slide. As the lever swings backward the retracting-spring is put under tension and the knots are ordinarily carried to one side of the general direction of the wire, so that at the instant of release there is pretty strong pressure of the knot against the lever. The operative swing of the lever tends to carry the diverging ends to one side of the wire, while the retracting-spring acts with considerable force to carry

the fork across the wire. The bearing-surface of the knot is broad enough to engage the members of the fork, or, in other words, is not small enough to pass between the parallel extension of the fork; but it is not much larger than is necessary to throw the lever, and it is somewhat elongated. Consequently when the impact end of a knot enters the space between the diverging ends of the members of the fork the force of the spring tends to cause the diverging surfaces to pinch the knot and interfere with its free release from the lever. The pinch on the knot wears the fork of the lever and increases the acuteness of the internal angle formed by the diverging ends. The increased acuteness increases the pinch correspondingly until the operation of the planter is seriously interfered with and the fork or the knots, or both, become inoperative. The knots may retain their form sufficiently to throw the forked levers for some time after being subjected to the undue strain of the pinching process; but ordinarily they will become compacted somewhat, thus changing the distance between knots and impairing the accuracy of the checking, and eventually they will become entirely inoperative. If the worn levers are frequently replaced, the difficulty may be lessened; but the frequent replacing of worn levers is of itself a difficulty, or at least an expense and annoyance, and even in new levers the pinch of the fork on the knots prevents perfect operation of the check-row mechanism.

To overcome the difficulties hereinbefore explained, I place rolling bearings in the ends of the parallel parts of the members of the forks of the lever at the points of divergence of the diverging ends, so that as the knots ride into the releasing-spaces they will be carried by the rolling bearings, as will hereinafter appear.

In the drawings forming part of this specification, Figure 1 is a plan of a horizontally-acting check-row lever embodying my invention. Fig. 2 is a side elevation of the lever. Fig. 3 is a representation of the inner surface of one of the members of the fork of the lever. Fig. 4 shows an end of a member of the fork. Fig. 5 is a side elevation of the forked end of

a lever, showing a modification of my invention. Fig. 6 shows the inner surface of one of the fork members represented in Fig. 5.

The lever 1 may be made in any desired form and may be adapted to swing either horizontally or vertically. In this instance it is designed to swing at 2 on a vertical pivot, and its extended and bored end provides means for connecting with a planter-shaft or slide-bar. The fork members 3 and 4 are clamped to the lever on opposite sides thereof by means of a bolt 5. They extend parallel one with the other for some distance, and at their ends they diverge, as shown at 6. Recesses 10 are formed in the inner surface of the members of the fork at the points of divergence of ends 6. Pins 7 extend inward into the recesses, and rollers 8 are journaled on the pins. The rollers are separated a space approximately equal to the distance between the parallel extensions of the fork members, and their opposed ends are slightly beveled, as shown at 9. Above the rollers the diverging ends 6 are set back to about the outer lines of the bevels of the rollers and their opposing surfaces are rounded somewhat, as shown at 11. (See Fig. 4.)

The smallest space between diverging ends 6 is greater than the impact-surface of the end 30 of the knot. The upper inner parts of the rollers are exposed, and when the knot passes the parallel bearing-surfaces of the fork they ride freely over the rollers unimpeded by the extensions 6. The bevels on the rollers are only sufficient to permit the fork to swing freely astride the wire after the knot is released and so the axes of the rollers are substantially parallel with the rolling bearings for the knots. In Fig. 1 the impact of a knot 40 with the fork is shown in solid lines, and broken lines are used to show the knot at the releasing-point of the fork. It is when the knot is at the position shown in broken lines that the rolling bearings are engaged and 45 pinch of the fork on the knot is avoided.

Figs. 5 and 6 show balls used in place of rollers to provide for rolling friction, the balls being shown at 8^a. In these figures the members of the fork are shown at 3^a and 4^a, the 50 balls are nested in recesses in the bars, the

diverging extensions 6^a curve downward and forward to retain the balls, as shown at 12, and lugs 13 are bent around the balls from outside the fork members to retain the balls in their recesses. These figures are suggestive merely of means for holding the balls in place, and the details are susceptible of various changes, the essential thing being to hold the rolling bearings in position to bear against the knot at the time the knot passes out of contact with the front surfaces of the parallel parts of the fork. 55

In the case of the ball-bearings the knot is released without tendency to wedge in the fork, and different points of contact are continuously presented to the knots, the same as in the case of the roller-bearings. 60

I claim—

1. A forked check-row lever having roller-bearings at the points of divergence of the 70 diverging ends of the members of the fork.

2. A forked check-row lever having roller-bearings at the points of divergence of the diverging ends of the members of the fork, such rollers being beveled or rounded-on their 75 opposing sides.

3. A forked check-row lever having roller-bearings at the points of divergence of the diverging ends of the members of the fork, the axes of such rollers being approximately 80 at right angles with the length of the fork.

4. A forked check-row lever having opposing recesses in the members of the fork at the points of divergence of the diverging ends thereof, and roller-bearings held in the recesses with their inner surfaces approximately in line with the inner surfaces of the parallel parts of the fork members. 85

5. A forked check-row lever having parallel fork members, recessed at their ends, roller-bearings in the recesses and diverging extensions of the fork members set back from the opposing ends of the roller-bearings and rounded, substantially as described. 90

In testimony whereof I sign my name in the 95 presence of two subscribing witnesses.

JOHN KAYLOR.
